UNITED STATES PATENT OFFICE

112,167

DESIGN FOR A COUNTER CHAIR

Ture I. Anderson, Merced, Calif.

Application August 22, 1938, Serial No. 79,493

Term of patent 14 years

To all whom it may concern:

Be it known that I, Ture I. Anderson, a citizen of the United States, residing at Merced, in the county of Merced and State of California, have invented a new, original, and ornamental Design for a Counter Chair, of which the following is a specification, reference being had to the accompanying drawing, forming a part thereof.

In the drawing:

I claim:

The ornamental design for a counter chair, as shown.

TURE I. ANDERSON.
